UNITED STATES PATENT OFFICE.

JAMES DOWSON JACKSON, OF SYDNEY, NEW SOUTH WALES, AUSTRALIA.

CONTINUOUS-FLOW WATER-HEATER.

1,230,167.

Specification of Letters Patent. Patented June 19, 1917.

Application filed September 23, 1915. Serial No. 52,230.

To all whom it may concern:

Be it known that I, JAMES DOWSON JACKSON, of 197 Hay street, Sydney, in the State of New South Wales, Commonwealth of 5 Australia, have invented certain new and useful Improvements in Continuous-Flow Water-Heaters Principally for Domestic Purposes, of which the following is a specification.

10 The present invention appertains to the heating of water during continuous flow and has been devised to effect an improved apparatus for such purpose embodying with simplicity of construction a high degree of 15 thermal efficiency and further the factor of being adapted for use as a sterilizing chamber; the apparatus or heater further being particularly applicable for household use as for heating water for baths.

20 According to this invention the water-heater consists essentially of a plurality of concentric water chambers separated by equal intervening spaces constituting the 25 flue passages each of said chambers being in communication at the bottom with a common supply, the heating element being introduced in a horizontal plane at the bottom of said flue passages and passing upwardly therethrough to a common outlet flue passage 30 also disposed horizontally and lying in a vertical plane above the said plane of application of the heating element.

The water chambers have a limited cross sectional passage area so that the water 35 passes upwardly therethrough in a thin column to better absorb the heat. At the top end of the heater the water from each chamber delivers to a common conductor which may be returned to deliver the volume to a 40 chamber formed on the inner wall of the innermost chamber.

The vertical front and rear ends of the heater, are closed and the front end may have a closely fitting door for the purpose of 45 introducing articles to be sterilized within the chamber formed in said inner wall.

To provide that forced draft will not operate on the flue passages the flue or vent pipe conveying the products of combustion 50 from the heater to the atmosphere has open communication with a vent communicating with said passages.

To secure greater heating surfaces for water chambers the sheet metal forming same may have the surface contacting with the 55 heating element corrugated or similarly staggered. Again, in lieu of each flue passage being one continuous space it may be partitioned or divided vertically into a series of parallel channels.

60 Referring now to the accompanying drawings depicting practical applications of this invention.

Figure 1 is a perspective view of complete heater, Figs. 2 and 3 being sections of same 65 on the planes 2-2 and 3-3 respectively of Fig. 1 and Figs. 4 and 5 sections on the planes 4-4 and 5-5 respectively of Fig. 2.

Figs. 6 and 7 are fragmentary perspective views showing modified arrangements of the 70 flue passages of the heater.

Referring to Figs. 1 to 5 inclusive:

The water pressure supply to the heater from pipe 10 communicates with the water jacket 11 disposed vertically about the fire 75 box 12 and with the inner of the concentric water passages 13 by means of a pipe 14 from branch pipe 15 (see Fig. 2) the water passing from the jacket 11 to the outer of 80 said passages 12 through the by-passages 16 disposed in the front and rear ends of said jacket (see Fig. 3).

The annulus contained between the concentric water passages 13 constitutes the bifurcated flue passage 17 proceeding from the 85 mouth of the horizontally disposed fire box 12 upwardly to the horizontal flue outlet 18 that communicates with the pipe 19 delivering into the open end of the vent 20. The flue outlet 18 lies parallelly above and in the 90 same plane as the fire box 12 the members or limbs of the bifurcated flue passage 17 being of equal length and cross sectional area so that the heat from the pipe or tubular gas burner 21 of any approved form mounted in 95 the fire box 12 distributes uniformly between the water passages 12 (see Fig. 2).

The water flowing upwardly through the 100 passages 13 is delivered directly from the inner chamber to the common delivery pipe 22 and to the latter from the outer chamber by means of the branch pipes 23 connected to a cross 24 (see Fig. 2) from which latter is led to the forward end of the heater the

pipe 25 having terminal tap 26 disposed outside the heater and also from said cross 24 the pipe 27 that passes out of the rear of the heater thence downwardly and is returned 5 into the bottom of the chamber 28 contained within the inner wall of the inner of the water passages 14 (see Fig. 3). This pipe 27 has a valve 29 provided therein as shown in Fig. 3.

10 The chamber 28 is employed for sterilizing or steaming purposes having longitudinal supporting rails or bars 30 provided therein for a tray 31 constructed of perforated material or meshed fabric.

15 In the front end of the heater a hinged door 32 is provided covering the space above the tray 31 in the chamber 28, said door being held in closed position by means of the catch 33 of any approved type.

20 The water entering the bottom of the chamber 28 below the tray 31 by means of pipe 27 is delivered from the front end of said chamber 28 by the pipe 34 while steam entering said chamber 28 is conducted to the 25 vent pipe 20 by pipe 35 passing upwardly from said chamber through the flue exit 18 as shown in Fig. 3.

To provide that small quantities of boiling water may be withdrawn from the heater a 30 closed receptacle 36 is provided mounted about an upward extension of the pipe 22 which delivers thereto through an elongated slot 37 and said pipe conveys the steam from said receptacle 36 to a constant level cistern 35 38 below the surface of which it terminates and delivers the steam for condensation.

The outer wall of the water jacket 11 forms a vertical base for the heater and stands within a tray 39 (see Fig. 1). The 40 burner 21 is connected to the main gas pipe 40 through a tap 41 a lighting orifice 42 being provided in the front wall of the heater as shown in Fig. 1.

The heater in use, the water supply flows 45 through pipes 10, 15 and 14 and the water jacket 11 to the concentric water chambers 13 thence flowing upwardly to the cross 24 from which it is delivered to the pipes 25 and 27. If the taps 26 and 29 of the pipes 25 and 27 respectively are both closed then the 50 heated water from the chambers 13 passes to the receptacle 36 unless the tap 37^a of the latter is also closed when the water will flow to the cistern 38.

55 The heat from the fire box 12 distributes itself uniformly through the limbs of the bifurcated flue passage 17 undue draft being prevented by having the mouth of the flue exit 18 equal in area to the mouth of the 60 fire box 12.

Referring now to Figs. 6 and 7 in which parts similar to those described with reference to Figs. 1 to 5 inclusive bear corresponding reference numerals.

In Fig. 6 the modified arrangement consists in vertically partitioning the bifurcated flue passage 17 proceeding from the fire box 12 into a vertical parallel series by means of the ribs 43 having horizontally disposed staggered projections 44 on opposing faces 70 as shown so as to present circuitous paths for the heat.

In Fig. 7 the modified arrangement consists in forming the walls of the flue passage 17 of vertically corrugated sheet metal the 75 walls being so fitted that the ridges contact as shown and thus said flue passage is divided into a parallel series each bifurcated and proceeding from the common fire box 12 to the common exit 18.

What I claim and desire to secure by Letters Patent is:—

1. In a continuous flow water heater, concentric water passages, a bifurcated flue passage formed between said water passages, 85 the limbs of said flue passage being of equal length and cross-sectional area, a common supply connected at the bottom of said water passages, a fire box arranged in a space forming the continuation of said flue passage, and an exit communicating at the top of said flue passage.

2. In a continuous flow water heater, concentric water passages whereby an annular chamber is formed, peripheral partitions to 95 form a series of bifurcated flue passages, the limbs of said flue passages being of equal length and cross-sectional area, the fire box communicating at the bottom with said flue passages and an exit connected at the top to 100 said flue passages.

3. In a continuous flow water heater, concentric water passages, a bifurcated flue passage within the annulus to form opposite water passages, a horizontal fire box at the 105 junction of said flue passage, and a flue exit disposed at the top end of said flue passage and in the same vertical plane as said fire box, said flue exit having the same cross-sectional area as the bifurcated flue passage. 110

4. An improved continuous flow water heater, comprising a pair of concentric water passages, a water jacket communicating with the outer of said water passages, a fire box within said water jacket, a bifurcated 115 flue passage originating at said fire box and surrounding the inner of said water passages, an exit connected to said flue passage, a horizontal flue interposed in the connection between the exit and said flue passage, 120 said horizontal flue being of equal cross-section and sectional areas of the bifurcated flue passages and being in communication with the atmosphere, water supply pipes connected to said water jacket and to the inner of said water passages, and a common delivery conductor connected to said water 125 passages.

5. In a continuous flow water heater, concentric water passages whereby an annular chamber is formed, partitions to form a vertical series of bifurcated flue passages, said partitions having staggered projections on opposing faces so as to provide circuitous paths for the heat passing therethrough, a fire box communicating at the bottom with
- 19 said flue passages, and an exit connected at the top to said flue passages.
- In testimony whereof I affix my signature in presence of two witnesses.

JAMES DOWSON JACKSON.
